By his Attorney,
Vernon M. Horan

UNITED STATES PATENT OFFICE

JOHN W. LONEY, OF BROCKTON, MASSACHUSETTS, ASSIGNOR TO O. A. MILLER TREEING MACHINE COMPANY, OF PORTLAND, MAINE, A CORPORATION OF MAINE

TREEING MACHINE

Application filed January 10, 1929. Serial No. 331,440.

This invention relates to machines for treeing boots or shoes and is herein illustrated as embodied in a treeing machine of the type disclosed in Letters Patent of the United States No. 1,268,837, granted June 11, 1918, 5 upon application of J. S. Hansen.

Treeing machines of this character are commonly provided with a plurality of expandable tree legs, either a pair as is common in so-called hand treeing machines or two pairs as is common in power treeing machines such as that illustrated in the above-mentioned Letters Patent. These tree legs are secured to a rotatable turret so that any one 10 of the tree legs may be brought into operative position. Each tree leg carries a tree foot adapted to be inserted in a shoe, and means is provided for operating expanding mechanism to cause the tree foot and leg to 15 fill completely the interior of the shoe and to stretch the leather tightly. For various reasons, such as simplicity, adaptability and sensitiveness, it is found desirable to provide an individually hand-operated device in connection with each tree leg by means of which 20 the operator can expand each leg after the shoe has been applied to it. One very successful arrangement is illustrated in the above-mentioned Letters Patent in which a 25 pivoted operating lever is directly connected to the expanding mechanism and is associated with a hand-operated lever which has a nose which presses against a cam surface on the operating lever and swings that lever 30 to expand the tree and then locks it in a predetermined position to hold the tree in expanded condition.

An object of the present invention is to provide an improved treeing machine having 40 operating means for the tree expanding mechanism which will apply pressure variably suited to different characteristics of the shoes to be treated, thus better adapting the machine for operating on both light weight 45 shoes and heavy weight shoes, for example, and which will nevertheless be still easier to operate.

To this end, one of the features of the invention resides in a novel automatic locking device, associated with the operator-con-

trolled means for the tree expanding mechanism, which is constructed and arranged to hold said means in any one of a plurality of positions. In the illustrated embodiment of the invention, the locking device is of the 55 cam type which jams in any one of an infinite number of positions in which it may be put whereby the tree expanding mechanism may be held under just the desired tension to cause the stretching action applied to the shoe to be treated to be suited to the character of the shoe upper of the shoe. At the same time, the operation of the machine is facilitated since it is only necessary for the operator to move a manually operable member, illustrated as a hand lever, just far enough to cause the expanding mechanism to apply the 60 requisite pressure to the given shoe.

The invention will now be described with reference to the accompanying drawings, in 70 which

Fig. 1 is a plan view of a fragment of a turret for a plurality of tree legs;

Fig. 2 is a detail in vertical section through the pivots of the respective levers;

Fig. 3 is a plan view on a reduced scale; and

Fig. 4 is a fragmentary elevation.

In the drawings, there is shown a fragment of a turret 10 pivoted for rotation 80 around a fixed upright rod 12 and carrying a plurality of tree legs 14. These legs may be of any suitable construction but are preferably of the type known as a "Miller tree" and shown in Letters Patent of the United States 85 No. 319,356, granted June 2, 1885 upon the application of A. D. Tyler, Jr. Each of these tree legs is equipped with a suitable tree foot adapted to support a boot or shoe and is arranged to be expanded to stretch the shoe 90 by moving an expanding rod 16 having a head 18 longitudinally of the tree toward the axis of the turret. For convenience in handling the shoe and in performing the various cleaning and treeing operations, each tree leg is 95 rotatably mounted on the turret for movement around the longitudinal axis of the leg and is held in one position by means of a latch 20 engaging a pin 22 on the leg, said latch being released in one position of the 100

turret by means of a cam 24 mounted on a bracket 26 secured to the upright rod 12.

Inasmuch as the parts associated with each tree leg are identical, only one set of parts will be described. In order to move the expanding rod 16 radially of the turret to stretch a shoe, there is provided an operating lever 30 pivotally mounted on the turret by means of a pivot stud 32 and forked at its free end at 34 (Fig. 2) for engagement over the expanding rod 16 back of the head 18 externally of the tree leg. This operating lever is swung around its pivot to expand a tree by an operator-controlled lever 40, illustrated as a hand lever, which has a short inner end provided with a cam roll 42 adapted to bear against a cam surface formed upon a hardened steel insert 43 in the operating lever 30. This cam surface is so shaped that the effort required to expand the tree leg is greatly reduced and wear upon the parts is practically eliminated by the use of the roll 42 and the hardened insert 43. The hand lever 40 is pivoted upon the reduced upper end 46 of a stud 44, extending through a boss 48 formed in the turret, and the stud is provided with a retaining collar 50 at its lower end.

After the tree leg has been expanded it is desired to lock the levers, and hence the tree, in any desired position, and to this end co-operating eccentric smooth-surfaced disks 52 and 54 are provided which are mounted at the upper ends of the respective studs 32 and 44. The locking disk 52 is held loosely in position just above the operating lever 30 by the head of the stud 32 which passes downward through a boss 56 on the turret and is held in position by a collar 58. On the other hand, the disk 54 is secured to the hand lever 40 both by means of a nut 60 at the upper end of the reduced portion 46 of the stud 44 and also by a pin 62. Since each of the disks 52 and 54 are eccentrically mounted upon their axes it is possible to lock the hand lever 40 in active position, as shown at the left of Fig. 1, with the tree leg expanded, by moving the locking disk 52 to the desired position with respect to the disk 54 so as to cause a frictional engagement between said disks such that any tendency for the hand lever 40 to be moved back to its original position will be immediately counteracted by jamming of the disks between the studs upon which they are carried. The construction is such that this jamming may take place in any one of an infinite number of positions and makes it possible, accordingly, to lock the hand lever and hence also the operating lever 30 in any position to which it is moved by the operator. A spring 64 extends between a hook 66 on the disk 54 and a hook 68 on the disk 52, this spring tending to draw the loose disk 52 into locking position. When it is desired to release the hand lever so as to contract the tree under the influence of a spring (not shown)

which is contained within the tree leg, it is possible to rotate the locking disk 52 by means of a handle 70 made integral with the disk. As in the patented machine, the hand lever 40 is also provided with a spur 72 adapted positively to engage a shoulder on the insert 34 on the operating lever 30 to limit the movement of the lever 40 to its released position.

It will be understood that the usual construction of such machines provides the turret alternately with right- and left-hand tree legs as indicated in one instance by the letter R shown in Fig. 1 upon the latch 20. Assuming then that the operator has applied a right-hand shoe to the tree leg at the front of the machine as viewed in Fig. 1, he will move the hand lever 40 toward him and in so doing will displace the operating lever 30 to draw back the expanding rod 16, thereby to expand the tree leg and stretch the shoe. The desirability of controlling the amount of stretching action so as to differentiate between the force applied, for example, to light kid shoes and that applied to heavy Cordovan shoes, will be self-evident. The improved construction herein illustrated allows the operator to apply just the desired amount of force completely to expand the tree leg within the shoe without unnecessary effort or without undue stretching effect. Having reached the desired position of the hand lever, that lever is immediately and automatically locked in position by the loose locking disk 52 to hold the operating lever 40 against the resilience of the work and the tension of the tree leg spring (not shown). The locking disk 52 is dragged along by the spring 64 so that it follows up the disk 54 and is always in position to jam that disk when the force applied by the operator to the lever 40 is discontinued. Just as soon as the operation is finished, however, and it is desired to release the tree leg so that it may be contracted by the spring within the tree leg, that release may be effected immediately, and with practically no effort at all, by pressing against the handle 70 on the loose disk 52 so as to move it aside against the tension of the spring 64. The arrangement provided, therefore, is not only easy to operate but is automatic in its operation and capable of holding the tree leg expanded in any one of an infinite number of positions. It will be noted that the arrangement described is simple and inexpensive to manufacture and is one which may readily be applied to existing machines without the necessity of replacing expensive parts.

Having thus described my invention, what I claim as new and desire to secure by Letters Patent of the United States is:—

1. In a machine for treeing boots and shoes, an expansible tree leg, operating means connected to said tree leg, operator-controlled

means for moving said operating means, and locking means of the cam type including a substantially smooth-surfaced member attached to the operator-controlled means and 5 constructed and arranged automatically to hold said operating means in any one of a plurality of positions to keep the tree leg in its expanded condition.

2. In a machine for treeing boots and 10 shoes, an expansible tree leg, an operating lever for expanding said tree leg, a manually operated lever for moving said operating lever, pivots for said levers, and co-operating locking means mounted on said pivots and 15 associated with said levers, said locking means being constructed and arranged to hold one of said levers locked in any one of a plurality of positions.

3. In a machine for treeing boots and 20 shoes, an expansible tree leg, a pivoted operating member directly connected to said tree leg, an operator-controlled member associated with said operating member constructed and arranged to move it to a position 25 for expanding the tree leg, and means for locking one of said members in any one of an infinite number of positions.

4. In a machine for treeing boots and 30 shoes, an expansible tree leg, an operating lever, an operator-controlled lever therefor, and an interacting locking device, associated with each of said levers constructed and arranged to lock both of said levers automatically in any one of an infinite number of positions.

5. In a machine for treeing boots and shoes, an expansible tree leg, an operating lever connected to said tree leg, an operator-controlled lever arranged to bear against said 40 operating lever to expand the tree leg, and continuously acting pivoted coating locking devices associated with said levers and constructed and arranged to lock one of said levers automatically in any adjusted position.

6. In a machine for treeing boots and 45 shoes, an expansible tree leg, parallel pivot studs, an operating lever pivoted on one of said studs and constructed and arranged to expand said tree leg, an operator-controlled lever pivotally mounted on said other stud and arranged to bear against said operating lever to move it, and eccentric locking disks carried by said studs and spring-pressed into 55 locking engagement, one of said disks being secured to the lever with which it is associated.

7. In a machine for treeing boots and 60 shoes, an expansible tree leg, parallel pivot studs, an operating lever pivoted on one of said studs and constructed and arranged to expand said tree leg, an operator-controlled lever pivotally mounted on said other stud and arranged to bear against said operating 65 lever to move it, eccentric locking disks car-

ried by said studs and spring-pressed into locking engagement, one of said disks being secured to the lever with which it is associated, and means upon the loose disk to rotate it into unlocked position.

8. In a machine for treeing boots and 70 shoes, a rotatable turret, an expansible tree leg mounted on said turret and having a tree expanding rod movable radially of the turret, co-operative operating and operator-controlled levers pivoted side by side upon the turret, said operating lever being connected to said expanding rod and said operator-controlled lever being arranged to bear against the operating lever to move it 75 to cause the expansion of the tree leg, and eccentrically mounted locking disks associated with said levers and spring-pressed into locking engagement to hold one of the levers in any one of its adjusted positions, one of said disks being secured to the lever with which it is associated.

9. In a machine for treeing boots and 80 shoes, a rotatable turret, an expansible tree leg mounted on said turret and having a tree 85 expanding rod movable radially of the turret, co-operative operating and operator-controlled levers pivoted side by side upon the turret, said operating lever being connected to said expanding rod and said operator-controlled lever being arranged to bear against the operating lever to move it to cause the expansion of the tree leg, eccentrically mounted locking disks associated with 90 said levers and spring-pressed into locking engagement to hold one of the levers in any one of its adjusted positions, one of said disks being secured to the lever with which it is associated, and a handle for moving the loose disk to release the lever.

In testimony whereof I have signed my name to this specification.

JOHN W. LONEY.
